HYDRAULIC JACK

Clifford Carman, Niagara Falls, N. Y.

Application May 13, 1935, Serial No. 21,220

1 Claim. (Cl. 254—93)

This invention relates to hydraulic jacks for motor vehicles and has for the primary object the provision of a portable device of this character which is electrically actuated, obtaining electrical energy from the motor vehicle so that the latter may be elevated without use of manual power and which will automatically stop operation when the jack becomes fully extended or reaches full elevating position.

With these and other objects in view, this invention consists in certain novel features of construction, combination and arrangement of parts to be hereinafter fully described and claimed.

For a complete understanding of my invention, reference is to be had to the following description and accompanying drawing, in which

Figure 1 is a vertical sectional view illustrating a hydraulic jack and operating mechanism therefor.

Figure 2 is a top plan view, partly in section, illustrating the same.

Figure 3 is a perspective view illustrating the cover and the base of the device.

Figure 4 is a detail sectional view showing the means for securing the cover to the base.

Referring in detail to the drawing, the numeral 1 indicates a base consisting of a plate in which opposite ends thereof are curved upwardly, as shown at 2, so that said base or plate may be readily slid upon the ground or other supporting surface without the base digging or catching into the ground. Removably secured to the base 1 is a cover or housing 3. The securing means between the cover or housing 3 and the base is preferably in the form of screw threaded studs 4 suitably secured to the base and extending through apertured flanges 5 of the cover or housing and having threaded thereon nuts.

Mounted upon the base 1 within the cover or housing 3 is a hydraulic jack 7, the construction and operation of which is conventional. The elevating element 8 of the jack 7 is adapted to pass outwardly through an opening in the top of the cover or housing. The operating medium of the jack is indicated at 9, whereby a pivotal movement thereof will cause a raising of the elevating element 8. A connecting link 10 is pivoted to the operating element 9 of the jack and is eccentrically pivoted to a wheel or disc 11 suitably secured to the shaft 12 of an electric motor 13. The motor 13 is mounted to the base 1 and has electrical conductors 14 connected therewith and which extend outwardly of the cover or housing 3 in the form of an extension cord. The extension cord is adapted to be electrically connected

or plugged in an electric circuit of a motor vehicle so that the electrical energy for the motor may be obtained from the electrical power source of the vehicle. Connected to the conductors 14 and located within the housing or cover 3 is a switch 15, the control lever thereof being indicated by the character 16 and is provided with an eye slidably receiving a rod 17 connected to the elevating element 8 of the jack. The lower end of the rod 17 is offset, as shown at 18, the purpose of which is to impart movement to the control lever 16 of the switch 15 when the elevating element 8 of the jack reaches substantially its full elevating position so as to break the electric circuit to the motor 13 and thereby stop operation of the jack.

The jack 7 is provided with the usual releasing valve or equivalent element 20 employed for lowering the elevating element 8 and connected to the control element 20 is a handle 21 extending through an opening of the housing 3 and equipped with a finger piece so that the operator may at any time desired actuate the control element 20 for the lowering of the elevating element 8 of the jack. The handle 21 may be of any desired length and may be employed by the operator for positioning the device under the axle of a motor vehicle.

The cover or housing 3 is equipped with a handle 22 so that the device may be conveniently carried from one place to another.

Having described the invention, I claim:

In combination with a hydraulic jack having an operating medium and an elevating element, a base supporting said jack, an electric motor mounted to said base and connected to said operating medium for actuating the elevating element, an electrical connection for said motor to be connected in an electric circuit of a motor vehicle, a switch connected to said electrical connection and to said elevating element for stopping the motor when said elevating element reaches its full elevating position, a cover mounted to said base with the motor and the major portion of the jack confined therein and provided with an opening to permit the elevating element to extend exteriorly of said cover, said base having opposite ends curved upwardly, a handle secured to said cover, and means for lowering the elevating element and extending exteriorly of the cover whereby said means may be employed for positioning the jack under an axle of the motor vehicle.
